MACHINE FOR LOADING BAGS AND THE
LIKE

Joseph Corrigan, Boston, Mass.

Application May 3, 1932. Serial No. 608,928

5 Claims. (Cl 226—104)

My invention is a machine for loading bags and other containers and it has for its object to provide a machine of this class of simple, efficient and inexpensive construction.

It is also an object of this invention to provide a light, portable, motor driven machine of the class designated which will be particularly adapted for use in a yard or other storage place for coal, coke and the like, and by means of which bags or other containers can be quickly, conveniently and accurately loaded, each with a measured quantity of the material that is being dispensed.

To these ends I have provided an improved machine for loading bags and other containers, said machine having the peculiar features of construction and mode of operation set forth in the following description, the several novel features of the invention being particularly pointed out and defined in the claims at the close thereof.

In the accompanying drawings:

Figure 1 is a side elevation of a loading machine constructed in accordance with my invention.

Figure 2 is a sectional plan view taken on the line 2—2 of Fig. 1.

Figure 3 is a section on line 3—3 of Fig. 2 with the addition of the hopper, hereinafter described, which is not shown in Fig. 2.

Figure 4 is a sectional detail of parts of the measuring drum.

Figure 5 is a detail of the detent means hereinafter described.

Figure 6 is an end view of the measuring drum hereinafter described.

The embodiment of my invention herein illustrated is a self-contained power operated portable machine especially adapted for use in a coal yard or the like to fill or load bags with coal or coke.

The machine herein illustrated comprises a frame 10 consisting, in most part, of lengths of angle iron riveted or otherwise fastened together to form an oblong rectangular structure within which most of the parts of the device are disposed, and having a base portion adapted to rest upon the ground.

Journalized in bearings 11 provided at one side of frame 10 near the ground is a transverse axle 12 carrying wheels 13 which are preferably supported just clear of the ground when the frame is in an upright position.

When it is desired to move the machine about from one place to another it is manually tilted toward the right, Fig. 1, until it is wholly support-

ed by the wheels 13 after which it can be trundled from one place to another quickly and easily.

At the top of the frame 10 is fixed a hopper 14 having oppositely disposed side walls and a back wall which slant downwardly and inwardly to an outlet 15 at the bottom of said hopper through which material from the latter is discharged at times into a cylindrical measuring drum that is indicated generally at 16.

The outlet 15 is extended downwardly by a spout 17 provided at the bottom of hopper 14 and the bottom edges of the opposite side walls of this spout are disposed close to the periphery of the drum 16 and arcuately concentric with the axis of the drum 16 so that there are no passages or openings at the opposite sides of the outlet 15 through which the material can escape sidewise.

The front wall of the spout 17 is a closure member 18 that is pivotally supported at its upper end by a pintle 19 to which it is fastened. This pintle 19 is journalized in bearings 20 provided upon the front of the hopper, and has fastened to one end thereof a rearwardly extending arm 42 that is yieldingly urged upwardly and normally held against an adjustable stop 43 by a coiled spring 44.

The inner side of the upper portion of the closure member 18 is flat and slants downwardly and inwardly from the lower end of the front wall of the hopper toward the axis of drum 16 as far as the periphery of the latter and from thence downwardly the inner side of the lower portion of the closure member provides an arcuate surface that is concentric with the axis of the drum and close to the periphery of the latter. This arcuate skirt portion of member 18 extends downwardly in front of the drum as far as the horizontal plane of the top of a delivery funnel 21 fixedly mounted on the frame 10 directly beneath drum 16, the lower portion of the latter being preferably disposed within the upper portion of said funnel.

The drum 16 comprises an intermediate interiorly and exteriorly cylindrical side wall that is rigidly connected with end spiders or heads 22 one of which latter is fastened at its middle, by welding or otherwise, to the inner end of a horizontal axle trunnion 23 and the other to the inner end of a similar axle trunnion 24. These two axle trunnions are axially aligned and journalized in bearings provided on frame 10.

The cylindrical side wall of the drum is made with a rectangular passage or port 25 whose length is less than the length of the interior of

the drum and which is midway between the end spiders 22.

Within each completely cylindrical end portion of the drum is arranged a circular sheet metal partition wall 26 that is adjustably held in position within the drum by means of a pair of screws 27. The screws 27 of each pair extend through threaded apertures provided in the adjacent end spider and the inner end of each is rotatably fastened to its partition wall 26 as shown in Fig. 4. Thus when the screws of each pair are manually rotated its partition wall is adjusted lengthwise of the drum thereby varying the volumetric capacity of the latter. As will be clear the screws 27 hold the walls 26 fixedly in adjusted position.

A given volume of coal of one grade or kind will weigh less than coal of another grade or kind and therefore it is an advantage to so construct the drum that its volumetric capacity can be varied as may be required by the kind or grade of coal that is being packaged.

The end spiders 22 may be disks of metal, as shown, formed with holes or ports 28 through which is discharged by gravity any dust or particles of coal which may find its way into the spaces between the partition walls 26 and the spiders 22.

The axle trunnion 23 has fixed thereon a member 29 provided with two radially disposed abutment arms 30 and 31 which are at opposite sides of the axis of said trunnion axle. Alongside of member 29, and loosely mounted on the axle trunnion 23, is a sprocket wheel 32 around which passes a flexible endless power transmitting chain 33 which is also in engagement with a sprocket wheel 34 fast on a transverse shaft 35 journaled in bearings on the frame 10 of the machine. Shaft 35 also has fastened thereon a pulley 36 connected by a belt 37 with a pulley 38 fast on the armature shaft of an electric motor M that is fixed in position on frame 10.

The motor M is adapted to be connected by circuit wires (not shown) with a source of current and a manually operated make and break switch (not shown) may be mounted on frame 10 and connected in circuit with motor M, if desired.

The endless chain 33 is provided with a laterally projecting arm 39 which is in the same vertical plane with the two abutment arms 30 and 31. When the motor M is operating the chain 33 is driven continuously in the direction indicated by the arrow in Fig. 1 and it will be clear that after the portion of said chain which carries the arm 39 is brought into engagement with sprocket 32, and as said arm travels around the axis thereof, it will pick up and move the arm 30 with it to the extent of one-half of a revolution at the end of which the arm 39 disengages the arm and moves away from sprocket 32 on a tangential path.

As pointed out above the radial abutment arms 30 and 31 are angularly disposed 180° apart so that when one of said arms is picked up by arm 39 and swung around the axis of trunnion 23 to the extent of one-half of a revolution, the other abutment arm takes its place in the path of arm 39 and will be similarly operated thereby the next time arm 39 makes the circuit of its orbit.

Thus when the machine is in use the drum 16 is intermittently turned step-by-step in a counter-clockwise direction (Fig. 1), each step movement being to the extent of one-half revolution.

The abutment arms 30 and 31 are set on axle trunnion 23 so that during alternate periods of

rest thereof the drum passage or port 25 is in register with the outlet 15 of the hopper and during the other periods of rest the passage 25 is at the bottom of the drum.

Thus each time the passage or port 25 is brought into register with the hopper outlet the drum is filled with coal or other material from the hopper and each time the drum is turned to bring its passage or port 25 at the bottom thereof its contents is discharged into the delivery funnel 21.

The funnel 21 is made at its bottom with an outlet 40 which extends through a spout 41 that is provided upon the exterior of the funnel and on which the mouth portion of a bag is adapted to be fitted telescopically so that each load of material that is discharged into the delivery funnel by the measuring drum is delivered into a separate bag applied to the spout 41 in this manner.

The chain drive for the abutment arms 30 and 31 not only effects intermittent step-by-step movement of the measuring drum but its length affords sufficient time between delivery operations of the drum for the operator to remove a filled bag from spout 41 and substitute an empty bag.

It will be clear that clogging at the hopper outlet 15 which would otherwise tend to stop the movement of the drum is prevented by the yielding closure member 18. Sticks of wood and other objects are often found in coal and except for the yielding closure member 18 would tend to clog and stop the operation of the machine.

During each period of rest of the measuring drum it is held against accidental rotative displacement by means of a spring pressed detent, herein shown as a ball, which at such times occupies one or the other of two sockets 46 provided upon the periphery of a wheel 47 fast on axle trunnion 24. The detent 45 and its spring 48 are mounted within a chamber 49 formed in a bracket 50 that is secured to the frame 10.

What I claim is:

1. In a machine of the character described, the combination with a rotatably supported measuring drum provided with a pair of abutments disposed upon opposite sides of the axis thereof, of a rotatably supported wheel disposed alongside of said abutments; a second rotatably supported wheel; means operable to rotate said second wheel, and an endless flexible power transmitting member supported by said two wheels and driven by said last mentioned wheel, said member having an arm projecting therefrom for engaging one of the abutments of said pair of abutments each time said arm traverses its orbit thereby to turn said drum step-by-step in one direction.

2. In a machine of the character described, the combination with a rotatably supported measuring drum provided with a pair of abutments disposed upon opposite sides of the axis thereof, of a rotatably supported wheel whose axis is coincident with the axis of said drum, said wheel being disposed alongside of said abutments; a second wheel; a motor for continuously rotating said second wheel in one direction, and an endless flexible power transmitting member supported by said two wheels and driven by said second wheel, said member having an arm for engaging the abutments of said pair individually in alternation as it repeatedly traverses its orbit thereby to intermittently rotate said drum step-by-step in one direction.

3. In a machine of the character described, the combination of a rotatably supported measuring drum provided with a supporting axle that is rigidly connected with one end thereof; a pair of radially disposed abutment arms fast on said axle, one at each side thereof; a wheel loosely mounted on said axle alongside of said abutment arms; a second wheel; a motor mounted on said frame for continuously rotating said second wheel in one direction, and an endless flexible power transmitting member supported by said two wheels and driven by said second wheel; said member having an arm for engaging the abutment arms of said pair individually in alternation as it repeatedly traverses its orbit thereby to intermittently turn said drum on its axis step-by-step in one direction. 80
- 10 4. A bag loading machine comprising a frame; a hopper fixed to said frame and having an outlet at its bottom; a hollow measuring drum rotatably supported by said frame beneath and in close proximity to said outlet so as to turn on a horizontal axis and so as to serve at times as a closure for said outlet, the side wall of said drum 85 being made with a passage adapted to register with said outlet so that said drum is filled by gravity with material from said hopper; a delivery funnel fixed to said frame beneath said drum into which the contents of the latter is delivered by gravity when said passage is below the axis of the drum, said delivery funnel having an outlet at its bottom through which its contents is discharged by gravity and a spout surrounding said outlet for holding the mouth 90 of a bag in position to receive the material that is discharged through said outlet; an axle journaled on said frame and connected with said drum; a pair of radially disposed abutment arms 95
- 15 fast on said axle, one at each side thereof; a wheel loosely mounted on said axle alongside of said abutment arms; a second wheel rotatably supported by said frame; a motor mounted on said frame for continuously rotating said second wheel in one direction, and an endless flexible power transmitting member supported by said two wheels and driven by said second wheel; said member having an arm for engaging the abutment arms of said pair individually in alternation as it repeatedly traverses its orbit thereby to intermittently turn said drum on its axis step-by-step in one direction. 100
- 20 5. In a machine of the character described, the combination with a fixed hopper having an outlet at its bottom and a hollow measuring drum rotatably supported beneath and in close proximity to said outlet having a side wall made with a passage adapted to register with said outlet so that said drum is filled by gravity with material from said hopper, of actuating mechanism for said measuring drum comprising a rotatably supported member that is connected with said drum and constructed with a pair of abutments disposed at the opposite sides of 105 the axis of said member; a rotatably supported wheel alongside of said member; a second rotatably supported wheel; means through which said second wheel is continuously rotated, and an endless flexible power transmitting member supported by said two wheels and driven by said second wheel, said power transmitting member having an arm for engaging said abutments individually in alternation as it repeatedly travels around said first-mentioned wheel thereby to intermittently turn said drum on its axis step by 110 step in one direction. 110
